ACOUSTIC DIAPHRAGM

Original Filed April 4, 1929

Inventor

Adolph A. Thomas

UNITED STATES PATENT OFFICE

1,980,235

ACOUSTIC DIAPHRAGM

Adolph A. Thomas, New York, N. Y., assignor to
American Telephone and Telegraph Company,
a corporation of New York

Original application April 4, 1929, Serial No.
352,396. Divided and this application July 20,
1932, Serial No. 623,555. Renewed August 24,
1934

1 Claim. (Cl. 181—32)

My invention relates to the art of sound-transmitting and reproducing devices, and its object is to provide a vibratory diaphragm of novel structure capable of use in any kind of telephone 5 transmitter and receiver. Broadly stated, my new diaphragm is made of a ferro-nickel alloy substantially unaffected by variations in temperature, whereby the diaphragm retains its original form or degree of tension without regard to climatic changes.

The single figure in the accompanying drawing is a face view of an acoustic diaphragm constructed in accordance with my invention. For convenience I have shown a circular membrane 10 mounted for vibratory movement in a frame 12. The membrane 10 is a thin disk of "Invar" or similar ferro-nickel alloy, and it is preferably supported under tension sufficiently high for proper operation. "Invar" is an alloy of approximately 37% nickel and 63% iron, and it is not affected by changes in temperature, so that the original tension of the diaphragm is preserved in all climates and seasons. Furthermore,

"Invar" is not liable to rust. When I describe by diaphragm as made of "Invar" or its equivalent, I do not mean that it must be composed entirely of that material, but substantially so.

The shape and size of diaphragm 10 are immaterial in the broad aspect of my invention, for they can be varied for the best results in any particular design of instrument, whether for receiving or transmitting sound. No operating means for the diaphragm is shown, because this invention is for the diaphragm itself, without regard to the other elements that go to make up a complete transmitter or receiver. My new diaphragm is especially useful for loudspeakers.

This case is a division of my pending application Serial Number 352,396, filed April 4, 1929.

I claim as my invention:

An acoustic diaphragm substantially composed of an alloy comprising approximately 37% nickel and 63% iron, whereby said diaphragm is substantially unaffected by changes in temperature.

ADOLPH A. THOMAS.
